UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

COVER FOR STRAIN INSULATORS.

Application filed November 14, 1919. Serial No. 338,012.

To all whom it may concern:

Be it known that I, ARTHUR O. AUSTIN, a citizen of the United States, residing at Barberton, in the county of Summit and 5 State of Ohio, have invented certain new and useful Improvements in a Cover for Strain Insulators, of which the following is a specification.

This invention relates to strain insulators 10 and the provision of means for protecting the insulators from leakage due to certain weather conditions, particularly to water on the surface of the insulator. The principal object of the invention is, therefore, to provide 15 an insulator with a protecting shell either of metal or some non-conducting material.

The invention consists in the novel construction, combination and arrangement of 20 the parts.

In the accompanying drawing—

Fig. 1 is a side elevation of a cover in which an insulator is shown in broken outline with strain members attached thereto.

25 Fig. 2 is an end view.

Fig. 3 is an end view of a modified form of insulator; and

Fig. 4 is an end view similar to Fig. 2 showing a cover supported at a distance 30 from the insulator by a spacing member.

In a strain insulator it is common to separate the guy wires or conducting members by a partition of the insulating material and to space the conducting members apart 35 by vanes which provide a leakage surface of considerable extent to increase the leakage path between the separated members, thereby preventing a flashover, except when subjected to high potential, or when the resistance of the leakage path is broken down. In 40 practice it may be that an insulator of this kind is so positioned that some electrical conducting liquid, such as water, covers the vanes in such a manner as to materially reduce the resistance of the leakage path 45 between the strain members so that a flashover will occur at a much lower potential difference than is intended. The present invention is for the purpose of minimizing this 50 danger to as great an extent as possible without adding to the size of the insulator itself by protecting the surface of the insulator.

An insulator 1 of the type shown in Figs. 55 1 and 2 has four radiating vanes 2 at right

angles to each other, and is formed with holes 3 also at right angles to each other and separated by the vanes 2. Through these holes 3 any suitable guy wires or strain members 4 are looped through each other so that they are separated by a partition in the insulator, and in the form shown these strain members are provided with headed extremities 5, which are engaged by socketed members 6, which have 60 inside openings 7 for admitting the headed extremities 5 to hold the strain members in place when the extremities are compressed so that the heads will be engaged in the sockets. To each member 6, a cable 8 is attached in any well-known manner.

A cover 9 is applied to the insulator only, and is preferably cylindrical in form, fitting closely over the insulator with beaded portions 10 at the ends of the insulator to hold 75 the cover in position thereon, the cover extending some distance beyond the beaded portion and, therefore, beyond the ends of the insulator, but usually terminating at some distance from the socketed members 6, 80 in which the strain members 4 are held. This shell may be of any desirable or suitable material, it is contemplated that it may be made of thin sheet metal, but it may also be of some insulating material, it being necessary to use some material which will protect the insulator against water, or any other substance for which protection is needed. The material of the cover may be either a conductor or a non-conductor as the leakage 90 path of the insulator is usually sufficient to afford the necessary resistance if the resistance of the path is not materially cut down.

As shown in Fig. 3, the same kind of a cover can be employed with an insulator 11 95 of different shape in which there are a great many more vanes or fins than shown in Fig. 2, the object of which is to increase the leakage path between the strain members. In both types of insulators the cover is supported by the extremities of the vanes, and the vanes themselves are uniform length, but it is obvious, of course, that a cover of this kind might be applied to an irregularly formed insulator in which some of the vanes 100 were not of sufficient length to engage the cover, and in fact the cover might be supported entirely free from contact with the extremities of the vanes by means of spacing members 12, as indicated in Fig. 4. 110

As this cover is preferably made of sheet metal or other sheet material, it may either be wrapped around the insulator and the ends fastened, or it may be made up in hollow or cylindrical form and pressed on or sprung in place about an insulator where it will be held in place by its own resiliency, as well as by the beaded grooves 10.

It will be apparent that the shortest surface leakage path between the conductors will be over one of the ribs 2 at points along the insulator where the conductors are in overlapping position. The points of contact between the cover 9 and the ribs 2 are equidistant from the separate conductors and since the surface of the insulator is substantially uniform in resistance the drop of potential to the conductors from any point of contact between the cover and the insulator 20 will be the same; consequently the points of contact will be at substantially equi-potential points on the insulator. This prevents any tendency that might otherwise exist for leakage currents to follow the cover from 25 one point to another on the insulator surface.

I claim:-

1. A strain insulator having radially extending vanes, conductors positioned between said vanes, and connected with said insulator for supporting a load on said insulator, and a surrounding sheet metal cover therefor directly engaging the edges of the vanes and supported between any two conductors by a single vane only.

2. The combination of a strain insulator having extending vanes with the outer edges all parallel and strain members separated thereby but looped through each other and 40 extending in opposite directions; and a cylindrical metallic cover fitting tightly over the edges of the vanes and extending beyond the ends thereof but with inwardly grooved portions adjacent the ends for engaging the 45 ends of the vanes and holding the cover in place.

3. A strain insulator having a pair of conducting strain members looped through each other and an insulating member with a partition spacing the looped portions apart and

with extending vanes forming a leakage path between the strain members, and a metallic cover supported by the outer edges of the vanes to protect the insulator, said cover coinciding with any single leakage path at a 55 single supporting position only.

4. A cover for a strain insulator comprising a cylindrical metal member fitting over an insulator and contacting therewith at peripherally spaced positions, the intermediate portions of said member being curved away from contact with said insulator with inwardly extending annular grooves near the end to hold the member in place on an insulator.

5. A strain insulator having extending vanes, and a protecting cover of sheet metal forming a closed figure the interior of which engages said vanes at peripherally spaced positions with curved intermediate portions 70 free from contact with said insulator which portions can be sprung to permit the cover to be slipped on and off said insulator over the vanes and held in place by its own resiliency.

6. A strain insulator comprising a dielectric member, interlinked load-supporting members insulated from one another by said dielectric member, said dielectric member having vanes extending from the body thereof and interposed between said load-supporting members to provide resistance between said load-supporting members, and a protecting shield of conducting material carried directly by the dielectric member and supported thereon at substantially equi-potential points.

7. The combination with an insulator of fragile dielectric material having longitudinally extending radial flanges thereon and supporting members of conducting material disposed in said flanges, of a protecting cover for said insulator of resilient metal supported directly by the outermost edges of said flanges and bowed outwardly between 95 the lines of support on said flanges.

In testimony whereof I have signed my name to this specification on this 31st day of October A. D. 1919.

ARTHUR O. AUSTIN.
